EXHAUST VALVE OF THE POPPET VALVE
TYPE OF INTERNAL-COMBUSTION EN-
GINESJulius Charles Haefeli, Selly Oak, Birmingham,
England, assignor to The Austin Motor Com-
pany, Limited, Northfield, Birmingham, Eng-
landApplication October 11, 1944, Serial No. 558,170
In Great Britain October 22, 1943

1 Claim. (Cl. 123—188)

1

The invention relates to exhaust valves of internal combustion engines and being of the poppet valve type; and has for its object to provide means to prevent such valves becoming unduly heated by the exhaust gases.

According to the invention that part of the valve stem, which lies in the exhaust passage and between the head of the valve and the valve guide, is surrounded by a shroud separate from the valve guide and which preferably has an internal diameter greater than the diameter of the valve stem so as to leave an annular space between the shroud and the stem.

The shroud may be fixed in relation to the cylinder head (or cylinder block as the case may be) being screwed into the inner end of the bore into which the valve guide is fitted; but the shroud may be an integral part of the head or cylinder block. A space should be left between the shroud and the valve guide to form a heat break and prevent any appreciable transfer of heat from the shroud to the valve guide.

The effect of the shroud is to screen the valve stem from the direct effect of the exhaust flame, and so to prevent undue heating of the valve stem, and consequently to allow of a greater proportion of heat from the valve head to flow to the valve guide thus reducing the temperature at the valve.

The shroud also prevents the flame from impinging on the portion of the valve stem which moves in and out of the guide; and so prevents burning of the lubricating oil.

The shroud may be of metal or of non-metallic substance such as porcelain or other material refractory to heat.

Convenient embodiments of the invention, as applied to an exhaust valve of the overhead type, are described with reference to the accompanying drawing in which:

Figure 1 is a vertical section through the valve, valve seat and valve guide and also through a shroud according to one form of the invention.

Figure 2 is a view corresponding to Figure 1, but showing a modification in which the shroud is integral with the cylinder head.

Referring first to Figure 1, A indicates a valve of the overhead type having a stem a. B is the valve seat formed in the cylinder head C. D the valve guide fitted into the cylinder head

in the usual manner and E the exhaust passage. F is a shroud surrounding the stem a of the valve. In the example illustrated in Figure 1 the shroud is assumed to be composed of metal; but it may be composed of porcelain or other material refractory to heat, if desired. It has an internal diameter somewhat greater than the diameter of the portion of the stem a which passes through it so as to leave an annular space G between the shroud and the valve stem and prevent the passage of heat by conduction from the shroud to the valve stem. The upper end of the shroud has an external screw thread adapted to screw into an internal thread at the bottom of the bore in the cylinder head into which the valve guide is fitted.

An annular shoulder f of the shroud below the screw thread g limits the distance to which the shroud can be screwed into the cylinder head, 20 and the length of the shroud above the plain portion is such that a space H is left between the top of the shroud and the bottom of the valve guide D, thus to form a heat-break and prevent direct conduction of heat from the shroud to the 25 guide.

Referring to Figure 2, the shroud F' is formed as an integral part of the cylinder head. In this case also the internal diameter of the shroud is greater than the external diameter of the 30 valve stem a' so as to leave a space G' therebetween. Immediately above the shroud the internal bore is widened out to receive the valve guide D' and a space H' is left between the bottom of the guide and the top of the shroud to 35 form a heat-break.

The application of the invention to an exhaust valve of the side-valve type will be understood from the above description, the shroud in such case being screwed down into the top of 40 the bore in the cylinder block into which the valve guide is fitted or being formed as an integral part of the cylinder block.

Having fully described my invention what I claim and desire to secure by Letters Patent is:

45 In an internal combustion engine, the combination of an exhaust valve of the mushroom type, a stem of said valve, a valve seat, a part of said engine having a bore in which is set a tubular valve guide in which said valve stem is 50 guided, an exhaust passage through which said
